UNITED STATES PATENT OFFICE.

HUBERT P. RICHARDS, OF NEW BRITAIN, CONNECTICUT, ASSIGNOR TO J. EVARTS TRACY, OF PLAINFIELD, NEW JERSEY.

SEWING-MACHINE.

SPECIFICATION forming part of Letters Patent No. 679,914, dated August 6, 1901.

Application filed September 12, 1898. Serial No. 690,730. (No model.)

To all whom it may concern:

Be it known that I, HUBERT P. RICHARDS, a citizen of the United States, residing in New Britain, in the county of Hartford and State of Connecticut, have invented certain new and useful Improvements in Sewing-Machines, of which the following is a specification.

This invention relates in a general way to sewing-machines of that class in which the 10 stitch-making mechanism includes a reciprocating needle, a rotary looper adapted for carrying successive loops, and means for reciprocating the needle and rotating the looper and whereby the loop of the needle-thread 15 may be formed and be engaged by and carried entirely around the looper to inclose a lower thread to form a lock-stitch or may be carried through a preceding loop to form a chain-stitch or a chain lock-stitch; and the 20 invention more particularly relates to a so-called "combined lock-stitch and chain-stitch" mechanism embodying instrumentalities normally operative for forming a lock-stitch and also embodying a stitch-changing 25 device shiftable into position to engage successive loops and to so act thereon as to effect a change in the form of stitch made.

An object of the invention is to provide a differential stitch-making mechanism including an adjustable tension device and automatically-operable adjusting means for varying the resistance or effective tension of the tension device on the needle-thread in accordance with the requirements as determined by 35 the varying conditions present in the making of different stitches and at different points in the operation of forming any particular stitch.

A further object of the invention is to provide in a stitch-making mechanism embodying a rotary looper adapted for carrying two loops simultaneously a stitch-changing device operative independent of the looper for engaging one loop and for holding the same in such position that the next succeeding loop 45 will during the rotation of the looper pass therethrough, a tension device for controlling the tension of the needle-thread, and means operatively with the stitch-changing device for decreasing the stress of the tension device 50 upon the needle-thread when the stitch-changing device is shifted into operative relation

with the looper and for increasing the stress when the stitch-changing device is thrown out of operative relation with the looper, as required when the stitch-making mechanism is 55 forming chain-strokes and lock-strokes, respectively.

A further object of the invention is to provide in a stitch-making mechanism embodying a rotary looper adapted for carrying a 60 plurality of loops simultaneously a stitch-changing device independent of the looper for successively engaging succeeding loops and for holding said loops in such position that every succeeding loop will pass through a preceding loop, a tension device for controlling the tension of the needle-thread, and two independently-operating means, one of which is automatically operated by a cam on the looper-driver shaft and is effective for positively varying the tension at predetermined 65 points in the rotation of the looper and the other of which is automatically operative with the stitch-changing device and is effective for changing the degree of tension on the needle-thread, according as a chain-stitch or a lock-stitch is being made. 70

In the drawings accompanying and forming part of this specification, Figure 1 is a vertical longitudinal section of a sewing-machine embodying my present improvements, parts being broken away. Fig. 2 is a horizontal section taken on a line corresponding to the dotted line *a a*, Fig. 1, showing the parts below said line. Fig. 3 is an end view 85 of the machine as seen from the left in Fig. 1. Fig. 4 is a vertical cross-sectional view taken on a line corresponding to the line *b b*, Fig. 1, looking toward the left in said figure. Fig. 5 is a cross-sectional view similar to Fig. 4, 90 taken on a line corresponding to the dotted line *c c*, Fig. 1, looking toward the left in said figure. Figs. 6, 7, 8, and 9 are perspective views of the looper, needle, a portion of the work-plate, and a piece of fabric, illustrating, 95 respectively, four successive positions of the parts during the formation of a lock-stitch and indicating the positions of the loops when the fabric is swung about the needle to form a stitch at an angle to the preceding stitch. Fig. 10 is an enlarged cross-sectional view of the tension device for the needle-thread and a por- 100

tion of its actuating instrumentalities, the said section being taken on a line corresponding to the dotted line $b\ b$, Fig. 1. Fig. 11 is a cross-sectional view of the parts shown in Fig. 10, taken on a line corresponding to the dotted line $e\ e$ in said figure and showing the parts above said line. Fig. 12 is a side view of a portion of the feed-adjusting device detached. Fig. 13 is a perspective view of the pivot-plug 10 of said feed-adjusting device detached. Fig. 14 is a diagrammatic view illustrating the relative movements of the needle and looper and their actuating devices.

Similar characters designate like parts in 15 all the figures of the drawings.

In the drawings only so much of a sewing-machine is shown as is deemed necessary to illustrate the application and mode of operation of my present improvements.

20 My improved sewing-machine will usually comprise a framework, (designated by A,) which may be of any suitable general construction, for carrying the working parts of the machine; a vertically-reciprocating needle-bar N, carrying the needle N' ; a horizontal needle-bar-actuating shaft D, (shown as a crank-shaft,) journaled in suitable bearings in the framework and operatively connected with the needle-bar by a crank and link in 25 the usual manner; a rotary looper S, disposed at an inclination to the path of movement of and below the needle-bar and having a plurality of loop-takers or hooks; a looper-guide G, supported by a bracket G' on the frame and extending partially around the looper; a looper-supporting driver H; a horizontal looper-actuating shaft D', supported in suitable bearings below the bed-plate of the machine; a main driving-shaft D², horizontally 30 disposed in parallelism with and at one side the axis of the looper-actuating shaft and having a crank operatively connected with the crank of the needle-bar shaft by a link or pitman D³ in the usual manner; a two-to- 35 three train of gears E between and operatively connecting the main driving-shaft and looper-actuating shaft; feed mechanism operated from the main driving-shaft; a presser-bar P, having a presser-foot 7 coöperating 40 with the feed-plate of the feed mechanism for holding the fabric; a rock-shaft D⁴, journaled in the framework at one side of the needle-bar-actuating shaft D and operatively connected with the presser-bar by a crank in 45 a well-known manner and having means whereby said shaft may be rocked to raise or lower the presser-bar; a stitch-changing device (designated in a general way by W) shiftable into and out of operative relation 50 with the looper and effective when in operative relation with the looper for engaging a loop and holding the same in such position as to permit the next succeeding loop to pass therethrough; means operated by the main 55 driving-shaft for actuating the stitch-changing device; a tension device (designated in a general way by T) for controlling the needle-

thread, and two independent tension-modifying devices, (designated by T' and T², respectively,) the former of which is controlled by a 70 cam on the main driving-shaft and is effective for varying the tension at predetermined points in the rotation of said shaft and the latter of which is in operative connection with the stitch-changing device and is effective for 75 operating the tension device to change the tension of the needle-thread when the stitch-changing device is shifted into or out of operative relation with the looper.

The framework of the machine, which may 80 be of substantially the same general construction as the framework of the machine described in Letters Patent of the United States No. 574,573, granted to Francis H. Richards January 5, 1897, to which reference may be 85 had, usually comprises a horizontal bed-plate 2, having a depending looper-guide-supporting bracket G' at the work-supporting end thereof, a hollow upright 4 at the opposite end of the bed-plate, a horizontal arm 5 above said 90 bed-plate, and a vertical needle-bar-receiving head 6 at the free end of the arm 5.

The needle-bar N and presser-bar P are shown, as in the patent referred to, axially coincident, the needle-bar being supported 95 for reciprocatory movement in the presser-bar, which is in turn supported for vertical movement in the head 6, and is furnished at the lower end thereof with the presser-foot 7, a resistance-spring (not shown) being in practice provided, as in said patent, for regulating the pressure of the presser-foot upon the fabric.

The rotary looper S may be similar in a general way to the discoidal loop-taker described 105 in the patent referred to and is supported below the bed of the machine for rotative movement in a plane oblique to the path of the needle, (see Fig. 1,) said looper being guided in its rotation and held against movement 110 transversely of its path of rotation by the parti-circular looper-guide G, which extends around the lower portion and has a raceway 115 for receiving the perimeter of said looper, such raceway being in practice of sufficient depth to permit a slight diametrical movement of said looper. Said looper will in practice be furnished with some suitable means—such, for instance, as that described in the 120 patent referred to, but not shown in the accompanying drawings—for carrying a lower thread, cop, or bobbin and will also be provided with some suitable tension device for the lower thread. In the form shown the looper is furnished with a set of three correspondingly-disposed loop-taking hooks, which are designated by h , h' , and h'' , respectively, and also has formed in the inner face 125 thereof a series of driver-sockets 8, disposed preferably concentric to the axis of the looper and equidistant to one another, which sockets are adapted for receiving corresponding driving-pins 9 upon driving-arms 10 of the driver H, which driver may be of the same general

construction as that described in the patent referred to. Said looper has also formed in the periphery thereof a series of needle-receiving grooves.

5 The driving-shaft D^2 and needle-bar-actuating shaft D are, as before stated, operatively connected by cranks and a pitman D^X , and consequently have a one-to-one ratio of movement, whereas the looper-actuating shaft—the looper having three equidistant hooks—is connected to the main driving-shaft by a two-to-three train of gearing E in such a manner as to have two complete rotations to every three complete rotations of the main 10 driving-shaft, and consequently has two-thirds of a complete rotation at every complete reciprocation of the needle-bar, the ratio of movement between the looper and needle being the same in the present instance as in 15 the patent referred to. The two-to-three train of gears E is shown comprising an internal gear-wheel 12, fixed to the end of the shaft D' , and a pinion 13, fixed to the end of the driving-shaft D^2 and meshing with said 20 internal gear.

25 The feed mechanism shown comprises two substantially parallel rock-shafts R and R' , located at opposite sides, respectively, of the looper-actuating shaft D' and journaled in 30 bearings below the bed-plate 2 of the machine; two cranks 14 and 15, fixed to the outer ends of the rock-shafts R and R' , respectively; a feed member K pivotally secured at one end to the outer end of the crank 14 and having the 35 opposite end thereof bifurcated and in shiftable connection with a stud 15', fixed to the outer end of the crank 15; two cranks 16 and 16', secured to the inner ends of the rock-shafts R and R' , respectively; a compound 40 feed-member-advancing linkage operatively connecting the crank 16 and eccentric 18, and a feed-member-elevating linkage operatively connecting the crank 16' and said eccentric, said feed-member-advancing linkage and 45 feed-member-elevating linkage being so constructed and disposed and so timed in their movements one relatively to the other that during one complete cycle of movements of the driving-shaft D^2 and eccentric 18 from 50 a normal ineffective position the elevating-linkage will be first shifted to impart a feed-member-elevating movement to the rock-shaft R' and its crank, after which the feed-member-advancing linkage will impart a feed-member-advancing movement to the rock-shaft R and its crank and after which the elevating-linkage will operate to depress the feed member, and the feed-member-advancing linkage will then operate to impart a re- 55 tractive movement to said feed member or feed-plate, the operations of the two linkages taking place in alternation. The feed-member-advancing linkage in the form thereof shown in the accompanying drawings comprises a short vertically-disposed link 19, pivoted at its lower end to a projection on the strap 20 of the eccentric 18, and a horizon-

tally-disposed link 21, pivoted at its inner end to the upper end of the link 19 and pivotally connected at its outer end to the free end of 70 the crank 16. The feed-member-elevating linkage is shown comprising a crank-shaft R^3 , disposed intermediate the rock-shaft R' and main driving-shaft D^2 and having two differently-disposed cranks 24 and 24', respectively, 75 a horizontally-disposed link 25, preferably formed integral with and constituting a part of the eccentric-strap 20 and pivotally connected at its outer end to one of the cranks, as 24, of the crank-shaft R^3 , and a vertically-disposed link 26, pivotally connected at its lower end to the crank 24' of said crank-shaft R^3 and pivotally connected at its upper end to the crank 16' of the rock-shaft R . The dispositions of the cranks and eccentrics of the 80 feed-member-elevating linkage will be such as to secure a comparatively short stroke of the feed-member-elevating crank 15 at each semirotation of the driving-shaft D^2 .

85 As a means for changing the working stroke 90 of the feed-plate K and simultaneously changing the working position of said feed-plate I have provided a feed-adjusting device, (designated in a general way by M ,) which in the preferred form thereof comprises a slide-bar 27, supported for horizontal movement in a way 27', formed in a portion of the framework below the bed-plate of the machine, and which slide-bar has at the inner end thereof a depending portion 28, which is pivotally and adjustably connected to the link 21 intermediate the ends thereof and constitutes the fulcrum on which said link swings and also governs the range of movement of 100 said link.

105 For the purpose of forming a sliding pivotal connection between the adjusting device M and link 21 the depending portion 28 of said device has a transverse socket 29 formed in one face thereof, in which is seated 110 a bifurcated plug or pivot 30, the bifurcated end of which plug straddles the link 21, said plug being supported for oscillatory movement in the depending portion 28 of said device M , as will be understood readily by reference to Figs. 12 and 13 of the drawings.

115 As a convenient means for shifting the adjusting device M to change the fulcrum of the link 21, and consequently the working stroke of the feed-plate K , I have provided a shifting device, which may be a screw extending through a guideway in the bed-plate of the machine (see Fig. 5) and into the slide-bar 27 of the adjusting device M and having at its upper end a knurled head, whereby the 120 same may be turned to hold the adjusting device in its adjusted position.

125 Inasmuch as the general operation of the looper and feed mechanisms in the present machine in forming a lock-stitch is somewhat similar to that of the same parts in the machine described in the patent referred to, a detailed description of this operation is deemed unnecessary, it being sufficient to

say that in forming a lock-stitch the successive loops *l*, which are formed on the descending movement of the needle, are successively engaged by the succeeding hooks 5 and carried around the looper during the rotation thereof to inclose the lower thread and form a lock-stitch, each preceding loop being drawn up by a succeeding loop as said succeeding loop is partially drawn out by the 10 looper during the rotation thereof, as will be understood by reference to Figs. 6 to 9, inclusive, of the drawings. In the organization of mechanism shown in the accompanying drawings the looper *S* will be constantly 15 rotated in one direction during the operation of sewing, preferably in the direction of the arrows in Figs. 3, 4, 5, and 6 to 9 of the drawings, and toward the front side of the machine.

20 As a convenient and simple means for changing the form of stitch resulting from the normal operation of the needle and looper mechanisms hereinbefore described without effecting a change in the direction of movement of the looper or feed device or in the 25 mode of operation of the several lock-stitch mechanisms—to wit, the looper mechanism, the needle mechanism, and the feed mechanism—I have provided a stitch-changing device (designated in a general way by *W*) which is in all essential characteristics substantially the same as the stitch-changing device described in my Patent No. 607,079, dated July 12, 1898, said stitch-changing device being shiftable into position for coöperating with the looper and being effective for engaging the upper portions of successive loops and for deflecting said portions laterally of the path of the needle, so that succeeding loops may pass through preceding loops and cause the stitch-forming mechanism to produce a chain-stitch or a chain lock-stitch. The construction and organization of the stitch-changing device are such that 40 the same may be thrown into or out of operative relation with the looper to change the form of stitch made by the stitch mechanism without the necessity of changing the direction of rotation of the looper or the direction 45 of movement of the feed mechanism and without the removal or substitution of parts, as heretofore necessary in machines of ordinary construction, and hence said device forms with the looper mechanism a change-stitch mechanism adapted for making different kinds of stitches as desired.

45 The stitch-changing device *W*, as shown most clearly in Figs. 2 and 4 of the drawings, comprises a loop-diverter *60*, (shown as a lever,) fulcrumed at *60'* below the bed-plate of the machine for horizontal oscillation across the path of the loops, actuating means for the loop-diverter, which is herein shown as a lever *62*, fulcrumed at *62'* at one side the axis 60 of the main driving-shaft *D²*, an actuating-rod *63*, pivotally connected at one end to the actuating-lever *62* and at its opposite end to

one end of the loop-diverter *60*, and a cam *64*, fixed to the driving-shaft *D²*, which has two oppositely-disposed working faces against 70 which a roll *64'* on the inner end of the actuating-lever *62* bears, said cam being adapted for advancing and retracting the loop-diverter *60* across the path of the loops, as will be understood by reference to Fig. 2 of the 75 drawings.

As a means for throwing the stitch-changing device out of and into operative relation with the looper I have provided a throw-out device *W'*, which is shown as a stud *62''*, supported for rotative and longitudinal movement in a vertical bearing formed in the framework, which stud has its lower end extending through the actuating-lever *62* and constitutes the support and fulcrum for said lever, and I have provided in connection with said stud a horizontally-disposed actuator *65*, (shown as a headed pin,) extending through an inclined or cam groove *66*, formed in the upright *4*, and having a head at the outer end 90 thereof whereby the stud *62''* may be rotated and simultaneously lowered to throw the outer end of the actuating-lever into operative engagement with the working surfaces of the actuating-cam *64*. This stud is provided with a depending lever-actuating projection *67*, so disposed (see Figs. 2 and 4) that when the stud *62''* is raised and rotated it will strike the lever at a point intermediate its fulcrum and the outer end and throw the 100 same toward the left, as seen in Fig. 2, thereby shifting the working end of the loop-diverter from its working position out of operative relation with the looper, the cam-groove *66* being upwardly inclined, as shown most 105 clearly in Fig. 3, so that when the actuator *65* is shifted toward the left the stud *62*, which carries the actuating-lever, will be raised and simultaneously rotated.

It will be obvious that other instrumentalities than those illustrated in the drawings may be employed for actuating the loop-diverter. Therefore it will be understood that I do not limit this invention to the particular means shown.

110 The actuating-cam *64* is shown constructed to impart both advancing and retracting movements to the loop-diverter; but it will be obvious that it might be constructed to impart a movement to said loop-diverter only in 115 one direction and other means be employed for imparting a movement thereto in the other direction.

In a sewing-machine of this class it is extremely desirable that means be provided for 125 varying the tension of the needle-thread at different points in the rotation of the looper, the preferred construction being one in which the tension of the thread may be decreased just before the engagement of a loop by a 130 loop-taker, so as to prevent breaking of the thread during the first stage of the drawing out of the loop, the tension being afterward increased just before the final drawing up of

the preceding loop. It is also important in sewing-machines having change-stitch mechanism for making different stitches that the tension should be changed in accordance with the requirements as determined by the kind of stitch being made, it being necessary, for example, to put a greater tension upon a thread for the formation of a lock-stitch than for the making of a chain-stitch. In the present case one of the main features of the invention is the provision of tension-modifying means automatically operative for increasing or decreasing the tension on the thread during the making of each separate stitch, and I also employ means for changing the tension by a definite amount when the mechanism is set for the making of another kind of stitch from that for which it may have been set previously. Hereinafter the tension-modifying means automatically operative during the making of any stitch will be termed a "tension-varying" device and will control the tension device coöperating directly with the thread, while the tension-modifying means, which determines the extreme degrees of tension for different stitches, will be termed a "tension-changing" device and in the preferred form of the invention will be controlled directly by the throwing of the stitch-changing device into and out of operation, it being obvious, of course, that when the stitch-changing device is inoperative and the mechanism operates to make a lock-stitch the tension should be quite high, while when the stitch-changing device is thrown into position to co-operate with the looper and deflect the loops carried therearound the tension should be modified materially, so that it will be much less than is necessary for the making of a lock-stitch.

For the sake of simplicity of construction a single thread-tensioning device—such, for example, as that indicated herein by T—will be used ordinarily, and this may be controlled by both the tension-varying device and the tension-changing device conjointly, these two tension-modifying devices being designated, respectively, by T' and T², as before stated.

The tension device shown in the drawings embodies two tension-plates, such as 35 and 36, one of which, as 35, may be supported on a suitable projecting portion or boss 37 of the framework, the other being loosely carried in this instance by a sleeve 38, supported for reciprocation in a longitudinal bore in the boss 37, an adjustable stop or stop-nut, such as 39, being secured to the upper screw-threaded end of the sleeve 38, between which stop and the tension-plate 36 a coiled spring 40, enclosing said sleeve, may work. In the construction shown the part which operates directly to vary the tension of this spring during each stitch-making operation is a rod 41, supported for reciprocation in the sleeve 38 and having a notched opening or recess at one side thereof, one wall of which forms an actuating member adapted to engage a pin,

such as 42, carried by the tension-plate 36 and extending through a slot in the sleeve 38. It will be apparent that when the rod 41 is lifted 70 the pin 42, and thereby the upper tension-plate 36, will also be raised slightly to decrease the tension on the thread between the plates. In the construction illustrated an actuating-rod 43 coöperates at its upper end 75 with the lower end of the rod 41 to lift the latter, a coiled retracting-spring being disposed between the lower headed end 41' of the rod 41 and some portion of the framework. At the lower end thereof the rod 43 80 may carry a roll 44, which may rest upon a circumferential cam-face 45 at one side of the cam 64 for the stitch-changing device, the spring at the upper end of the rod 43 serving to maintain the roll in contact with such cam-face 45. 85

The tension-changing device which I prefer to use embodies a short lever, such as 46, Fig. 10, having a ball-bearing support 47 between its ends, this lever being mounted in 90 a suitable opening in the framework. At its inner end the lever 46 engages the sleeve 38 near the lower end of the latter, and at its outer end said lever is in position to be operated by a thrust-rod to lower the sleeve and 95 the stop-nut 39 to increase the tension when the mechanism is set for the making of a lock-stitch, this tension being decreased, of course, as soon as the rod 49 is lowered. At its lower end said rod 49 is connected with the stud or 100 knob which controls the position of the stitch-changing device W and is operated thereby.

From the above description it will be seen that the tension on the needle-thread will be varied automatically by the operation of the rod 43 during the making of each stitch, whatever the character of the latter, and that the tension will be increased or decreased by a certain definite amount by the action of the rod 49, according as the mechanism is set for 110 the making of a lock-stitch or a chain-stitch.

No claim is herein made to the feed mechanism shown and described, for it constitutes the subject-matter of my concurrently-pending application filed April 12, 1900, Serial No. 115 12,516.

Having described my invention, I claim—

1. In a sewing-machine, the combination, with stitch-forming mechanism, of a thread-tensioning device, a stitch-changing device, 120 and automatically-operative tension-varying means controlling said thread-tensioning device and coöperating with the stitch-changing device.

2. In a sewing-machine, the combination, 125 with stitch-forming mechanism, of a thread-tensioning device; a stitch-changing device; and means controlled by the stitch-changing device for actuating the thread-tensioning device to decrease the tension upon the thread 130 when the stitch-changing device is thrown into operative position and to increase said tension when the stitch-changing device is thrown to its inoperative position.

3. In a sewing-machine, the combination, with stitch-forming mechanism embodying a rotary looper, of a thread-tensioning device; a stitch-changing device working on 5 the loops of the thread; and a tension-changing device operatively connected with said stitch-changing device.

4. In a sewing-machine, the combination, with stitch-forming mechanism including a 10 rotary looper, of a thread-tensioning device; automatically-operative tension-modifying means controlling said thread-tensioning device and operative for actuating the latter during each rotation of the looper to vary the 15 tension on the thread; a stitch-changing device; and a tension-changing device controlled by said stitch-changing device.

5. In a sewing-machine, the combination, with stitch-forming mechanism normally operative for making a stitch of one kind, of 20 feed mechanism; a stitch-changing device independent of said feed mechanism and controlling the making of a stitch of another kind; a thread-tensioning device; and a tension-changing device controlling said thread-tensioning device and controlled by said 25 stitch-changing device.

6. In a sewing-machine, the combination, with stitch-forming mechanism normally operative for making a stitch of one kind, of 30 feed mechanism; a stitch-changing device independent of said feed mechanism and controlling the making of a stitch of another kind and shiftable into and out of operation; a thread-tensioning device; and a tension-changing device controlling said thread-tensioning device and controlled by said 35 stitch-changing device.

7. In a sewing-machine, the combination, with stitch-forming mechanism normally operative for making a stitch of one kind and embodying a rotary looper, of feed mechanism; a stitch-changing device independent of 40 said feed mechanism and controlling the making of a stitch of another kind and shiftable into and out of operative relation with the looper; a thread-tensioning device; and a tension-changing device controlling said 45 thread-tensioning device and controlled by said stitch-changing device.

8. In a sewing-machine, the combination, with lock-stitch-forming mechanism, of a chain-stitch-forming device shiftable into and out of operation; a thread-tensioning device; 55 and a tension-changing device controlling said thread-tensioning device and controlled by said chain-stitch-forming device.

9. In a sewing-machine, the combination, with stitch-forming mechanism normally operative for making a stitch of one kind and embodying a rotary looper having a plurality of loop-taking hooks, of a stitch-changing device controlling the making of a stitch of another kind and automatically shiftable into 60 engagement with successive loops a plurality of times during each rotation of the looper; a thread-tensioning device; and a tension- 65

changing device controlling said thread-tensioning device and controlled by said stitch-changing device.

10. In a sewing-machine, the combination, with stitch-forming mechanism, of a thread-tensioning device; a pair of tension-modifying devices; a shiftable stitch-changing device located for working on the loops of the 75 thread; and means connecting said stitch-changing device with one of the tension-modifying devices.

11. In a sewing-machine, the combination, with stitch-forming mechanism, of a stitch-changing device; a thread-tensioning device; a tension-changing device; a separately-operative tension-varying device controlling the thread-tensioning device conjointly with 80 said tension-changing device; and means for automatically operating said tension-varying device during the making of each stitch.

12. In a sewing-machine, the combination, with stitch-forming mechanism normally operative for making a stitch of one kind, of a 85 stitch-changing device controlling the making of a stitch of another kind; a thread-tensioning device; a tension-changing device controlling said thread-tensioning device and controlled by said stitch-changing device; a 90 separately-operative tension-varying device controlling the thread-tensioning device conjointly with said tension-changing device; and means for automatically operating said tension-varying device during the making of 95 each stitch.

13. In a sewing-machine, the combination, with stitch-forming mechanism embodying reciprocating needle mechanism and a rotary looper, of a tension device for the needle-thread; a shiftable stitch-changing device; and tension-changing means controlling said 100 tension device and thrown into action when the stitch-changing device is shifted.

14. In a sewing-machine, the combination, with stitch-forming mechanism embodying reciprocating needle-actuating mechanism and rotary looper-actuating mechanism, of a tension device for the needle-thread, a stitch-changing device; and automatically-operative 105 tension-modifying means controlling said tension device, controlled by a part of the looper-actuating mechanism and co-operating with the stitch-changing device.

15. In a sewing-machine, the combination, with stitch-forming mechanism embodying needle-actuating mechanism and looper-actuating mechanism and normally operative for making a stitch of one kind, of a stitch-changing device controlling the making of a stitch 110 of another kind; a tension device for the needle-thread; a tension-changing device controlling said tension device and controlled by said stitch-changing device; and a separately-operative tension-varying device controlling 115 said tension device conjointly with said tension-changing device and operative by a part of the looper-actuating mechanism during the making of each stitch.

16. In a sewing-machine, the combination, with stitch-forming mechanism embodying a needle and a looper and normally operative for making a stitch of one kind, of a stitch-changing device controlling the making of a stitch of another kind and operative for deflecting each loop and holding it in such deflected position until a succeeding loop has passed therethrough; a thread-tensioning device; and a tension-changing device controlling said thread-tensioning device and controlled by said stitch-changing device.
17. In a sewing-machine, the combination, with stitch-forming mechanism, of a tension device embodying a pair of tension-plates and a spring; a tension-changing device controlling said spring; a separately-operative tension-varying device controlling said spring conjointly with said tension-changing device; and means for operating said tension-varying device automatically during the making of each stitch.
18. In a sewing-machine, the combination, with needle mechanism and a looper, of

change-stitch mechanism, feed mechanism; a tension device embodying a pair of tension-plates and a spring, and a tension-changing device independent of said feed mechanism controlling said tension device and controlled by the change-stitch mechanism and settable for different degrees of tension in accordance with the character of stitch being made.

19. In a sewing-machine, a tension device embodying a support, a pair of tension-plates, a tension-changing sleeve having a stop, a spring encircling said sleeve between the stop and one of the plates, and a tension-varying rod slidable in said sleeve and coöperative with the spring, in combination with stitch-forming mechanism, and separately-operative sleeve-actuating and rod-actuating devices at least one of which is controlled by said stitch-forming mechanism.

HUBERT P. RICHARDS.
